ADJUSTABLE RULING PEN

Robert D. Shomo, Detroit, Mich.

Application February 20, 1951, Serial No. 211,823

3 Claims. (Cl. 120—109.5)

1

This invention relates to drafting implements, and more particularly to an inking pen provided with means for adjusting the width of the line which may be drawn thereby.

A main object of the invention is to provide a novel and improved adjustable inking pen which is simple in construction, which is easy to manipulate, and which enables the draftsman to accurately reproduce a line of any desired width.

A further object of the invention is to provide an improved ruling pen which involves inexpensive parts, which is sturdy in construction, which is easy to adjust, and which enables a draftsman to select a correct line width by merely adjusting the pen without requiring the line to be tested on an auxiliary piece of paper to determine whether the width thereof is satisfactory.

Further objects and advantages of the invention will become apparent from the following description and claims, and from the accompanying drawings, wherein:

Figure 1 is a side elevational view of an improved ruling pen constructed in accordance with the present invention;

Figure 2 is a vertical cross-sectional view taken on line 2—2 of Figure 1;

Figure 3 is a side elevational view similar to Figure 1, but showing the nibs of the pen in separated relationship;

Figure 4 is an enlarged cross-sectional detail view taken on line 4—4 of Figure 1;

Figure 5 is a fragmentary perspective detail view of the abutment member employed for separating the nibs of the pen of Figure 1 to obtain a desired line width.

Referring to the drawings, the pen is generally designated at 11 and comprises a tubular shank 12 to one end of which is threadedly secured the pen body 13. The body 13 is formed with the opposed bowed, resilient nibs 14, 15 having the tapered points 16 and 17' which are biased toward each other by the resiliency of the nibs 14 and 15. Designated at 17 is an elongated shaft member which extends slidably and rotatably through the tubular shank 12 and has secured to its lower end, as viewed in Figure 1, the oval cam head member 18. Designated at 19 is an inwardly extending bracket element integrally formed on the neck portion of the nib 14, said bracket element being formed with a V-notch 20 which receives and serves as a bearing for the shaft element 17, as shown in Figure 4. Designated at 21 is a cap member which fits slidably and rotatably over the top end of the shank 12, as viewed in Figure 1, the end of the shaft member

2

17 being rigidly secured to cap or handle 21, as by being embedded therein in the manner shown in Figure 2.

The points of the nibs 14 and 15 may be separated as desired by moving the cap member 21 downwardly on the shank 12, as viewed in Figure 1, whereby the head 18 exerts a spreading action on the power portions of the nib members 14 and 15. Alternatively, the points 16 and 17' may be separated by rotating the cap member 21 on the shank 12, since the oval shape of head 18 provides a camming action responsive to the rotation of the shaft 17 relative to the nibs 14 and 15. To obtain a predetermined degree of separation of the points 16 and 17' responsive to rotation of the cap 21, the cap may be provided with an index mark 22, and the shank 12 may be inscribed with longitudinal reference lines 23 registrable with the mark 22, each reference line 23 representing a different width of inked line to be drawn. With the head 18 arranged so that the nib points 16 and 17' are just in contact and with said head engaging the inside surfaces of the nibs 14 and 15 at opposite points on its minor axis, the nib points 16 and 17' may be separated to a predetermined degree by rotating the cap 21 to bring index mark 22 into registry with a line 23 of the desired width. Obviously, as above described, it is also possible to adjust the width of the line to be drawn by moving the cap 21 downwardly on the shank 12, as viewed in Figure 1.

In use, the handle or cap 21 will be moved downwardly on the shank 12 to a position where the cam head 18 separates the nibs 16 and 17' to the desired degree, the handle or cap may then be rotated so that a desired width between the nibs may be obtained with the index mark 22 registering with the reference lines 23. Since the cam head 18 is selectively adjustable along the interior surface of the respective nibs 16 and 17', a different value of width between the nibs will result at different predetermined positions of the cam head 18, as the handle 21 is rotated. Hence, it follows that when a line of desired width is to be drawn, the handle will be moved to place the cam head 18 at the location at which the nibs are separated to the required distance. This will cause the index mark 22 to register with the reference lines 23 at a definite location to give a certain reading. Then, if the draftsman wishes a line wider or narrower than the first or base line, he merely rotates the handle 21 and can judge the change in the desired direction by the reading of the index mark with relation to the reference lines. To return to the base or

first line, the draftsman simply again rotates the handle to the original index reading. It follows, then, that the longitudinal adjustment determines the first or base width of line to be drawn by the ruling pen and the rotational adjustment is employed to vary the width of the base line. Additionally, with the base line width predetermined, the handle can be rotated so that the widest possible separation of the nibs result (Figure 3) so that the draftsman may wipe the ink from the nibs with a cloth or rag and then return the nibs to the original separated width by rotating the handle in the opposite direction until the index mark is moved to the original registration location with relation to the reference lines.

It will be readily apparent that while the above description has been directed toward a ruling pen for ruling straight lines, the same structure may be employed in an inking compass for inking circles, the above-described structure being employed in place of the pen conventionally employed in an inking compass.

While a specific embodiment of an improved ruling pen has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A ruling pen comprising a shank having an axial bore extending therethrough, spaced oppositely disposed outwardly bowed resilient nibs carried by and extending longitudinally from said shank, said nibs converging as they recede from the shank, a shaft extending through the bore and adapted to rotate and move longitudinally relative to the shank, a cam head carried by the shaft for rotation and longitudinal movement therewith between the nibs, said cam head being adapted to engage the nibs and separate them to regulate the distance between the ends thereof remote from said shank, and a handle fixed to the shaft adjacent the end of the shank remote from the nibs for rotating the shaft and moving it longitudinally through the shank.

2. A ruling pen comprising a shank having an axial bore extending therethrough, spaced oppositely disposed outwardly bowed resilient nibs

carried by and extending longitudinally from said shank, said nibs converging as they recede from the shank, a shaft extending through the bore and adapted to rotate and move longitudinally relative to the shank, a cam head carried by the shaft for rotation and longitudinal movement therewith between the nibs, said cam head being adapted to engage the nibs and separate them to regulate the distance between the ends thereof remote from said shank, a bearing carried by a nib and facing the opposite nib, said bearing engaging the shaft adjacent the cam head for holding the shaft in alignment with the bore, and a handle fixed to the shaft adjacent the end of the shank remote from the nibs for rotating the shaft and moving it longitudinally through the shank.

3. A ruling pen comprising a shank having an axial bore extending therethrough, spaced oppositely disposed outwardly bowed resilient nibs carried by and extending longitudinally from said shank, said nibs converging as they recede from the shank, a shaft extending through the bore and adapted to rotate and move longitudinally relative to the shank, a cam head carried by the shaft for rotation and longitudinal movement therewith between the nibs, said cam head being adapted to engage the nibs and separate them to regulate the distance between the ends thereof remote from said shank, a handle fixed to the shaft adjacent the end of the shaft remote from the nibs for rotating the shaft and moving it longitudinally through the shank, said handle having an index mark thereon and said shank having longitudinal reference lines thereon registrable with said mark so that a predetermined separation of the nibs may be obtained.

ROBERT D. SHOMO.
